RIDING SPUR

Betty J. Markim, 10064 Gamma St.,
Baton Rouge, La. 70814

Filed Apr. 7, 1967, Ser. No. 6,569

Term of patent 14 years

(Cl. D30—31)

FIG. 1.

FIG. 2.

FIGURE 1 is an elevational perspective view of a riding spur, showing my new design;

FIGURE 2 is an elevational view of the riding spur of FIGURE 1 attached to a boot, said boot being shown for illustrative purposes only.

I claim:

The ornamental design for a riding spur, substantially as shown and described.
